Primary Examiner — Mitchell I. Siegel*(74) Attorney, Agent, or Firm* — Rebecca Hanovice; Michael Catania; Sonia Lari**CLAIM**

The ornamental design for a putter head, as shown and described.

DESCRIPTION

FIG. 1 is a rear perspective view of the putter head claimed herein;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing is included for the purpose of illustrating unclaimed subject matter and forms no part of the claimed design.
